CLAIM

I claim an ornamental design for a fitness hoop, as shown and described.

DESCRIPTION

FIG. 1 is an top perspective view of a fitness hoop showing my new design;

FIG. 2 is a right perspective view thereof;

FIG. 3 is a magnified portion as designated in FIG. 2;

FIG. 4 is a bottom perspective view of FIG. 1;

FIG. 5 is a front elevational view thereof;

FIG. 6 is a right elevational view thereof;

FIG. 7 is a top plan view thereof; and,

FIG. 8 is a left elevational view thereof.

The broken line circles depict the bounds of the magnified portion and form no part of the claimed design.

1 Claim, 8 Drawing Sheets
